UNITED STATES PATENT OFFICE.

AUGUST GERSTNER, OF NEW YORK, N. Y.

RAILWAY-CROSSING.

No. 905,689.

Specification of Letters Patent.

Patented Dec. 1, 1908.

Application filed September 21, 1907. Serial No. 393,942.

To all whom it may concern:

Be it known that I, AUGUST GERSTNER, a citizen of the United States, and resident of the borough of Brooklyn, in the city and State of New York, have invented a new and useful Improvement in Railway-Crossings, of which the following is a specification.

The objects of my invention are to provide a railway crossing having its crossing rails so shaped that the car wheels will be supported on their flanges instead of on their treads when passing over the crossing thus eliminating the jar and noise incident to the usual jumping of the car wheels across the spaces in the tops of the rails left open for the passage of the wheels of a car on the crossing track, and also to provide a quick and inexpensive method of replacing the intersecting portions of the rails when it is desired for any reason so to do.

A practical embodiment of my invention is represented in the accompanying drawings, in which

Figure 1 represents my improved railway crossing in top plan, the parts intermediate the intersecting portions of the rails being broken away, Fig. 2 is a section in the plane of the line A—A of Fig. 1, looking in the direction of the arrows, a car wheel being shown in dotted lines in several different positions along one of the track rails, Fig. 3 is a detail perspective view of my improved socket piece for holding the intersecting portions of the rails, and Fig. 4 is a similar view of one of the intersecting rail portions.

The pairs of intersecting track rails are denoted by 1, 2, and 3, 4, respectively.

The tops of each set of intersecting rails on which the treads of the car wheels are supported are gradually inclined downwardly toward their points of intersection, as shown at 5, 6, so that, as each car wheel approaches the intersection of the track rails, the flange of the car wheel will gradually engage the track rail along which it is traveling, the treads of the car wheel at the same time being gradually separated from the track rail, until finally said wheel is entirely supported upon its flange.

The top surfaces 7 of the track rails between the points of intersection are preferably left depressed so that the car wheel will be supported by its flange until the wheel has passed both of the intersecting track rails.

To facilitate the replacement of those por-

tions of the rails which immediately intersect and are consequently subject to the most wear, I provide socket pieces 8 which are intended to be firmly embedded in the ground or securely fastened in whatever place desired and which are so formed as to receive and snugly embrace the intersecting portions of the rails. I preferably make these intersecting rail portions in one piece as shown at 9 for the main purposes of strength, alinement of the rails and ease of removal.

The socket piece 8 and the intersecting rail portion 9 are provided with bolt holes 10, 11, which register when the parts are in position and which are intended for the insertion of bolts 12 which serve to hold the intersecting rail portion 9 in place in the socket piece 8. The socket piece 8 is also fitted to receive the ends of the main rails and bolts 13 are provided for securing the ends of the main rail in place in the said socket piece.

When, for any reason, such as wear or breakage, it is desired to renew the intersecting rail portions, the bolts 12 may be removed and the intersecting rail portion 9 taken from its socket piece 8. A similar intersecting rail portion may then be inserted in the socket piece and fastened in place by said bolts. It will be readily seen that this is an easy, inexpensive, simple and effective means of replacing worn out intersecting rail portions and one which does not involve the disturbance of any other portions of the track.

The structure hereinabove described permits the car wheels to pass over the intersecting track rails without noise and jar and it eliminates the undue wear on the car wheel treads which results from the usual method of jumping across the spaces in the track rails at the intersecting points with the other track rails, and it also provides a method of easily replacing any worn or defective portions of the rails at their intersection.

It is to be understood that I do not limit myself to the construction herein shown and described as the above is only one way of carrying out my invention, but

What I claim is:—

1. In a railway crossing, intersecting rail portions, intermediate rail sections having their top surfaces in the same plane with the top surfaces thereof and outer rail sections having their top surfaces inclined downwardly toward the top surfaces of said inter-

seeting rail portions, and meeting said top surfaces of said intersecting rail portions at a level therewith.

2. In a railway crossing, intersecting rail portions, socket pieces fitted to receive them, intermediate rail sections having their top surfaces in the same plane with the top surfaces of the intersecting rail portions, and outer rail sections having their top surfaces inclined downwardly toward the top surfaces of said intersecting rail portions.

3. In a railway crossing, socket pieces, intersecting rail portions removably secured therein, intermediate rail sections having

their top surfaces in the same plane with the top surfaces of the intersecting rail portions and outer rail sections having their top surfaces inclined downwardly toward the top surfaces of said intersecting rail portions.

In testimony, that I claim the foregoing as my invention, I have signed my name in presence of two witnesses, this twelfth day of September 1907.

AUGUST GERSTNER.
